KNITTING MACHINE

Henry Harold Holmes, Leicester, England, assignor to Wildt and Company Limited, Leicester, England, a British company

Application January 5, 1935, Serial No. 523
In Great Britain September 20, 1934

8 Claims. (Cl. 66—25)

This invention consists in improvements in or relating to knitting machines and to fabrics made thereon and is an improvement in or modification of the invention described or claimed in the specification of British Letters Patent No. 388,829. In the aforesaid prior specification a knitting machine having two needle beds was described with long and short butt needles in at least one of those beds, in combination with a circumferentially adjustable stitch cam for the needles of at least one bed, and also for the needles of at least one of the beds independent adjustable clearing cams, one of which is operable on all needles and the other of which is operable only on needles of one particular length of butt.

According to the present invention the improvement or modification consists in a knitting machine comprising in combination two needle beds with needles arranged therein for rib knitting, patterning means for knitting patterned rib fabric and an adjustable knitting cam in one or in each of the needle beds, whereby the knockover points of the two cams can be adjusted into and out from coincidence one with the other to enable the knitting to be relatively tightened or loosened as and for a purpose to be described hereinafter. Conveniently, a single adjustable cam is provided in one of the needle beds operative on all the needles.

In order that the invention may be more clearly understood some preferred examples will now be described with the aid of the accompanying drawings, in which

Figure 1 illustrates a development of a portion of the cylinder cam box of a cylinder and dial machine, looking outwardly from the axis of the machine, with a pattern wheel located in position beneath it.

Figure 2 is a section on the line 2—2 of Figure 1 looking in the direction of the arrows and showing also a portion of the dial needle bed, and the dial cam cap therefor.

Figure 3 is a plan looking from above in Figure 1 indicating the arrangement of dial cams and cylinder and dial cam-operating means for one feed.

Figure 4 is an elevation of the parts shown in Figure 3.

Figure 5 is a perspective view of a detail of the clearing cam controlling means.

Figure 6 is a view similar to Figure 1 showing a modified construction, and

Figure 7 is a section on the line 7—7 of Figure 6.

Like reference numerals indicate like parts in the several figures of the drawings.

The general arrangement and construction of the machine illustrated in Figures 1 and 2 is similar to that described and illustrated in the aforesaid prior specification and only those parts necessary to the understanding of the invention are shown.

Briefly described, a needle cylinder 10 is surrounded by the usual cam box 11 and is surrounded by a dial needle bed 12 with a dial cap or cam box 13. The cam boxes 11 and 13 rotate together with a lower plate 14 which surrounds the cylinder and is formed with a driving bevel gear 15 to which a main power drive is transmitted. In each needle trick, both in the dial and in the cylinder, is a needle 16 and in the cylinder each needle has an associated sliding jack 17 the lower portion of which is of a springy nature and tends normally to move outwardly from the needle trick to bring a lower butt 18 over a lifting cam 19. The latter also travels in company with the plate 14. Associated with each sliding jack 17 is a swinging jack 20 the function of which is, by selection, to be pressed against the lower extremity of the sliding jack 17 to move the lower butt when required out from the path of the cam 19.

The swinging jacks are provided with butts 21 arranged at varying heights according to the pattern required and these butts are engageable by cams 22 all of which are pivotally mounted to swing on a pin 23 carried in a bracket 24. The latter also supports, by means of a spindle 25, a trick wheel 26, in the tricks of which are secured bits 27 that also have butts arranged at different heights in accordance with the pattern requirements. The trick wheel 26 is preferably advanced around its axis step by step one or more times in each revolution by any preferred means. Such means is of common form and is well known so that illustration thereof is unnecessary. On each such step by step advance a different bit 27 is presented to the cams 22 thereby selecting one or more of them according to the butts provided on the bit 27. In the example illustrated in Figure 2 the bit on the right is shown as having a butt at the level of each cam, whereas that on the left is shown as being devoid of butts entirely. The former will swing all the cams together about their axes 23 and the cams as they come into register successively with the swinging jacks 20 will advance any such jack which has projecting from it a butt 21. Thus, all the swinging jacks 20 with butts 21 will

be moved so that the butts 18 of the associated needle jack are clear of the cam 19 and none of the associated needles 16 will be raised for the purpose of knitting. On the other hand, the bit 27 on the left of the trick wheel will actuate none of the cams 22 and consequently none of the swinging jacks 20 will be actuated by the cam, thus permitting the butts 18 of the sliding jacks to be engaged by the cam 19 and the needles 16 will thus be raised in succession until the next movement of the trick wheel around its axis. Any arrangement of butts between the two extremes illustrated in Figure 2 may be employed and thus selection of needles to be raised for taking a yarn at the feed associated with the particular trick wheel in question is under control of that trick wheel.

The trick wheel 26, cams 22, jacks 20 and 17 together with cam 19 and the co-operation of these various parts are all well understood and are similar in all essential respects to the mechanism described in prior United States Patent No. 1,867,644 to which reference may be made for a fuller understanding of this part of the mechanism of the present invention.

The trick wheel may thus take the place of the usual clearing cam for the cylinder needles and is selective in its action for patterning purposes; but in the dial a fixed or adjustable clearing cam will be provided, for example an adjustable cam similar in its operation to the cam 109 described in connection with Figure 4 of the specification of prior British Letters Patent No. 388,829. In place, however, of such a clearing cam the dial may also be furnished with a trick wheel or wheels and when such devices are employed either for the cylinder or the dial it is to be understood that there will generally be one such wheel for each feed.

In this construction all the needles in both needle beds will have butts of the same length and this is one respect in which the present invention differs from that described in the aforesaid prior British specification No. 388,829.

One of the needle beds or each of them will have an adjustable stitch cam whereby the knock-over points of the cams in the two beds can be brought into or out from coincidence. In the example illustrated in Figures 1 to 5 the dial cam box is intended to be provided with an adjustable stitch cam 37 and the cylinder is furnished with an adjustable stitch cam element 28 which is angularly adjustable about the axis of the machine, that is to say, circumferentially with respect to the cylinder cam box. The cylinder cam system at each feed will comprise the usual latch opening cams 29, the adjustable stitch cam element 28 together with its associated lower cam 30. The stitch cam as a whole is not necessarily adjustable circumferentially and in the form shown in Figure 1 the cam is in two parts. That which acts upon the needles for the first portion of their downward movement is fixed as at 31 and the part 28 serves to complete the downward movement and terminates at the knock-over point 32.

The lower portion of the cam 28 is formed with external rack teeth 133 which mesh with a pinion 33. The latter is carried on a spindle 34 to the upper end of which is secured an arm 35 which projects beyond the cam box into the path of an adjustable abutment 38. Another arm 41 freely mounted also on the spindle 34 is connected by a link 39 with the outer end of an arm 36 which is mounted to rotate on a

spindle 40. The abutment 38 is adjustable vertically to different heights to engage at will the ends of either of the arms 35 or 36 and of a further arm 42 which is mounted to rock on spindle 43 fixed in a bracket 44 secured to the cam 5

Depending from the lever 41 is a rod 45 having at its lower end a cam face 46 which, when the link 39 is swung to the left of Figure 4, will engage a cooperating cam face 47 provided on a 10 swinging catch 48 pivotally mounted on the stud 49. The catch has a slot 50 to engage with a rod 51 extending radially from the pinion 33 to hold the latter in the position of adjustment shown in Figures 3 and 4 against the 15 tension of a spring 52 which is anchored at one end to the arm 35 and at the other end to a fixed pin 53. The catch 48 is normally pulled upwardly into engagement with the rod 51 by means of a tension spring 54 anchored at one 20 end to the catch and at the other end to a fixed pin 55.

To the dial stitch cam 37 is pivotally connected one end of a link 56, the other end of which is itself pivotally connected at 57 to an arm 58. 25 The latter is secured to a pivot 59 to turn about the axis of this pivot and the latter is gear-connected at 60, 61 to a second arm 62 pivoted on a pin 63 to which the gear 61 is secured. Thus by engagement of the arm 58 or the arm 30 62 with an abutment similar to 38 but not illustrated, the arm 58 can be rocked in either one direction or the other about the spindle 59 and by means of the link 56 will move the dial stitch cam 37 to one or the other extreme positions 35 illustrated in dotted lines in Figure 3.

With the apparatus so far described, a knitting operation can be carried out as follows:—

Let it be assumed that knitting has commenced with a plain 1 x 1 rib. For this purpose the 40 needles in the cylinder and dial will be arranged to take the yarn alternately and during this rib knitting the trick wheel 26 will be arranged to present a bit 27 similar to that on the left of the wheel shown in Figure 2. Thus all the cylinder needles will be raised successively and all the dial needles will be similarly projected by means of a fixed clearing cam 64. The step by step actuating mechanism for the trick wheel 26 will conveniently be bluffed out of action, during this plain rib knitting, and movement of the wheel will be thus arrested. Thus, while 1 x 1 rib knitting is in progress the same bit 27 will be operative all the time.

During this form of knitting the cylinder stitch 55 cam element 28 will have been adjusted to the position in which it is shown in Figure 1 in which position its knock-over point 32 is out of coincidence with the knock-over point 65 of the dial stitch cam. This adjustment will have been effected by moving the abutment 38 to a position to engage the arm 35 to swing the latter towards the left in Figures 3 and 4. The result of this is to shift the cam element 28 to the left in Figure 6 due to the engagement of the spur 60 wheel 33 with the rack on the cam element and the movement of the latter is from the position illustrated in Figure 6 to that shown in Figure 1.

When the knock-over points of the cylinder and dial stitch cams are thus brought out of coincidence, the cylinder needles will be caused to descend their combined stitch cam 31, 28, in advance of the retraction of the dial needles, because the knock-over point 32 of the cylinder 75

stitch cam is now moved to the right (in Figure 3) of the line 66 which represents the line of coincidence of the two knock-over points when the parts are in the position of Figure 6. Consequently the cylinder needles will draw yarn over the dial needles while the latter still remain projected and the subsequent retraction of the dial needles will cause the latter to draw their loops from the yarn already drawn by the cylinder needles. The result will be a relatively tightly knitted 1 x 1 plain rib fabric.

When sufficient plain rib knitting has been made the pattern wheel 26 will be put into operation so that on each pass of the yarn, selected cylinder needles only will be raised to take the yarn. At the same time the cam element 28 will have been moved back to the position illustrated in Figure 6 to bring its knock-over point into coincidence with that of the dial stitch cam 65. In other words, the two knock-over points will lie on the line 66 of Figure 3. This is brought about by adjusting the abutment 38 into the path of the arm 36 so that the latter is now turned in a clockwise direction as seen in Figure 3. This is effected by reason of the fact that relative rotation of the arm 36 (about the axis of the machine) with reference to the abutment 38 is in the direction of the arrow in Figure 3. By thus swinging the arm 36 about its pivot 40 the link 39 forces the cam surface 46 of the member 45 into engagement with the cam surface 47 and thus swings the catch 48 downwardly about its pivot 49. This releases the rod 51 whereupon the spring 52 pulls on the arm 35 and rotates the spindle 34 in an anti-clockwise direction as viewed in Figure 3.

Patterned rib fabric can now be knitted with the aid of the trick wheel 26 and during this portion of the operation all the dial needles will be successively projected to take yarn. The selective action on the cylinder needles, however, may be utilized to produce any preferred form of patterning by the formation of tuck or miss stitch effects according to the height to which the cylinder needles are normally adjusted without assistance from the trick wheel 26. As the knock-over points of the two stitch cams are now in coincidence, each dial needle when it is retracted will be moved substantially simultaneously with an adjacent cylinder needle if such needle is in operation. Consequently, each dial needle and each active cylinder needle will operate to draw its own loop of yarn freely from the yarn supply with the consequence that the fabric which is now knitted will not only be patterned but will be of a looser character.

If desired, the cylinder may be provided with an adjustable clearing cam 69 pivotally mounted at 70, and this clearing cam may replace the action of the pattern wheel during plain rib knitting and will serve to elevate all the cylinder needles while the wheel 26 remains idle. When patterned rib fabric is to be knitted, however, the cam 69 will be automatically lowered to an inoperative position shown in chain lines in Figure 1. The mechanism for actuating the cam 69 is as follows:—

Mounted externally of the cam box on the spindle 70 is an arm 71 and co-operating with the outer end of this arm is a wedge surface 72 provided at the end of a swinging arm 73. The latter is pivotally mounted on a stud 74 received in a bracket 75 projecting from the cam box and the arm 73 can be rocked about its pivot by engagement with an abutment such as 38.

Thus, when it is desired to raise the cam 69 into the full line position of Figure 1 the abutment 38 is adjusted to engage the arm 73 so as to swing it inwardly and to bring its wedge surface 72 beneath the arm 71, thereby turning the latter in a clockwise direction in Figures 4 and 5. The effect of this is to turn the spindle 70 to raise the cam 69 and it is retained in this raised position by means of a catch rod 76 passing through the cam box and operated from the rocking arm 42 by a rigid connection 142. A spring 143 anchored at one end at 144 presses with its other end against the part 142 so as normally to tend to press the catch rod 76 inwardly. The inner end of the latter has a bevelled face 176 which permits the cam 69, when it is raised, to snap past the end of rod 76 and in doing so to press the latter inwardly against the pressure of spring 143. When the cam 69 has reached the full-line position in Figure 1 spring 143 returns rod 176 to pass a recessed portion of the latter beneath cam 69 as clearly shown in Figure 1, whereby the cam is held in its raised position. When it is again desired to lower the cam 69, at a time when patterned fabric is to be made, the abutment 38 will be moved into engagement with the arm 42, thereby to draw the catch rod 76 out from engagement with the cam 69, whereupon a pull-over spring 77, anchored at one end to a pin 78 projecting from the boss of the arm 71 and at the other end to a fixed pin 79, will return the arm 71 and spindle 70 in an anti-clockwise direction.

When an adjustable dial stitch cam is provided as in Figure 3, the movements of the cams 37 and 28 can be individually of a less degree than when only an adjustable cam 28 in the cylinder cam box is provided. Nevertheless, the same degree of separation between the two cams can be thus obtained and in some instances it may be preferable to provide for an adjustable stitch cam in both cam boxes.

In Figures 6 and 7 a machine has been illustrated to which reference numerals similar to those employed hereinbefore represent similar parts; but in this case only the stitch cam element 28 is adjustable, there is intended to be no adjustable stitch cam for the dial needles nor is there an adjustable clearing cam such as 69. While this results in a simple construction of 50 mechanism the function is substantially similar to that of the previously described example.

In a further example of knitting which can be produced on either machine, the knitted web may be made to commence with, only on the 55 needles of one needle bed; for instance, the cylinder needles, thereby producing a plain stockinette fabric. After a sufficient length of this knitting has been produced the dial needles, which hitherto had been held retracted in an inoperative position may be thrown into operation thereby producing either a plain rib fabric as above described or a patterned rib fabric.

The mechanism for rendering the dial needles operative or inoperative at will may be of any 65 well known form and as of itself it constitutes no part of the present invention and is in accordance with known common practice it is thought that no illustration of this feature is necessary.

While in the foregoing the patterning effect 70 of the wheel 26 has been described as employed for the production of tuck or miss stitch effects it is quite obvious that the cam 19 may be utilized to lift selected needles for other patterning purposes as, for instance, for taking a plating thread. 75

Also it is obvious that jacquard knitting may also be produced with the aid of jacquard mechanism in place of the pattern wheel described. Furthermore, any other preferred patterning means 5 may be employed without departing from the invention.

The invention also includes knitted fabric having the characteristics of the formations above described.

10 I claim:

1. A rib knitting machine comprising in combination two needle beds each with a set of needles therein, patterning means for knitting patterned rib fabric, and an adjustable knitting cam element comprising a knock-over portion co-operating with at least one set of needles, which cam element is adjustable in a direction transverse to the lengths of the needles whereby the knock-over points of the knitting cams for 15 the two sets of needles can be moved into and out from coincidence for the purpose described.

2. A rib knitting machine comprising in combination two needle beds each with a set of needles therein, patterning means for knitting patterned rib fabric, and adjustable knitting cam elements comprising knock-over portions co-operating with the two sets of needles, which cam elements are adjustable in directions transverse to the lengths of the needles whereby the knock-over points of the knitting cams for the two sets of needles can be moved into and out from coincidence for the purpose described.

3. A rib knitting machine comprising in combination two needle beds each with a set of needles therein, patterning means for knitting patterned rib fabric, an adjustable knitting cam element comprising a knock-over portion co-operating with at least one set of needles, which cam element is adjustable in a direction transverse to the lengths of the needles, a pattern controlled automatically actuating means for adjusting said cam element whereby the knock-over points of the knitting cams for the two sets of needles can be moved into and out from coincidence, for the purpose described.

4. A rib knitting machine comprising in combination two needle beds each with a set of needles therein, patterning means for knitting patterned rib fabric, an adjustable knitting cam element comprising a knock-over portion co-operating with at least one set of needles, which cam element is adjustable in a direction transverse to the lengths of the needles whereby the

knock-over points of the knitting cams for the two sets of needles can be moved into and out from coincidence for the purpose described, and an adjustable clearing cam for at least one of the needle beds.

5. A circular rib knitting machine comprising two needle beds each with a set of needles therein, patterning means for knitting patterned rib fabric, and an adjustable knitting cam element comprising a knock-over portion co-operating with at least one set of needles, which cam element is circumferentially adjustable in the machine whereby the knock-over points of the knitting cams for the two sets of needles can be moved into and out from coincidence for the purpose described.

6. A circular rib knitting machine comprising two needle beds each with a set of needles therein, patterning means for knitting patterned rib fabric, adjustable knitting cam elements comprising knock-over points co-operating with both sets of needles, which cam elements are each circumferentially adjustable in the machine whereby the knock-over points of the knitting cams for the two sets of needles can be moved into and out from coincidence for the purpose described.

7. A circular rib knitting machine comprising in combination two needle beds each with a set of needles therein, patterning means for knitting patterned rib fabric, and adjustable knitting cam element comprising a knock-over point co-operating with at least one set of needles, which cam element is circumferentially adjustable in the machine, and pattern controlled automatically actuating means for adjusting said cam element whereby the knock-over points of the knitting cams for the two sets of needles can be moved into and out from coincidence for the purpose described.

8. A circular rib knitting machine comprising two needle beds each with a set of needles therein, patterning means for knitting patterned rib fabric, an adjustable knitting cam element comprising a knock-over portion co-operating with at least one set of needles, which cam element is circumferentially adjustable in the machine whereby the knock-over points of the knitting cams for the two sets of needles can be moved into and out from coincidence for the purpose described, and an adjustable clearing cam for at least one of the needle beds.

HENRY HAROLD HOLMES.
